Fig. 10

FIG. 1 is a top plan view of a portable radio phonograph, or similar article, showing my new design, with the cover thereof in closed position;

FIG. 2 is a bottom plan view thereof;

FIG. 3 is a side elevational view thereof;

FIG. 4 is an end elevational view thereof, as viewed from the top of FIG. 1;

FIG. 5 is an end elevation view thereof, as viewed from the opposite end;

FIG. 6 is a top plan view similar to FIG. 1, but with the cover removed;

FIGS. 7 and 8 are opposite side elevational views thereof, with the cover removed; and

FIGS. 9 and 10 are opposite end elevational views thereof with the cover removed.

I claim:

The ornamental design for a portable radio phonograph or similar article, substantially as shown.
